UNITED STATES PATENT OFFICE.

WILLIAM F. SEXTON, SR., AND WILLIAM F. SEXTON, JR., OF TORONTO,
ONTARIO, CANADA.

BALANCING ATTACHMENT FOR DOORS.

SPECIFICATION forming part of Letters Patent No. 245,666, dated August 16, 1881.

Application filed May 18, 1881. (No model.)

To all whom it may concern:

Be it known that we, WILLIAM FRANCIS SEXTON, Sr., and WILLIAM FRANCIS SEXTON, Jr., both of the city of Toronto, in the county of York, in the Province of Ontario, Canada, have invented a certain new and useful Balancing Attachment for Hinged Doors, of which the following is a specification.

The object of the invention is to provide for a hinged door a balancing attachment positive in its operation, easily applied, and durable in its construction; and it consists, essentially, of a weight attached by a strap, cord, or chain to a spindle extending from the pivotal point of the hinge, and so arranged that it may be adjusted upon the spindle to secure the effective power of the weight in order to close the door or to hold it open at any desired point.

In the drawings, Figure 1 is a side elevation of a door provided with our improved balancing attachment arranged to close the door from whichever side it may be opened. Fig. 2 is an end view of Fig. 1, showing the arrangement of our balancing attachment. Fig. 3 is an enlarged plan of our balancing attachment. Fig. 4 is an enlarged end view of the same, and Fig. 5 an enlarged side view. Fig. 6 is a plan of the attachment applied to the door to operate it in one direction. Fig. 7 is a side elevation of Fig. 6. Fig. 8 is an end view, showing the balance-weight connected to the spindle by the interposition of bevel-gears. Fig. 9 is a side view of the latter figure.

While our invention is applicable to all the classes of doors, it has been specially designed for heavy doors made to open on both sides, and which are now commonly supplied with spring-hinges. These spring-hinges it is known soon weaken and require constant adjustment to insure their working.

In the drawings like letters indicate corresponding parts in each figure.

A is the door, hinged or pivoted as represented, and provided with a spindle, B, extending from the pivotal point of the door, preferably below the floor, and resting on a suitable bracket, C, screwed to the joists. An adjusting set-screw, C', is applied to the bottom of the spindle B in such a manner that the door may be readily adjusted closer or farther away from the floor, as circumstances may require. A pul-

ley, D, (or, when the attachment is arranged as shown in Figs. 8 and 9, a bevel-spur wheel,) is keyed or otherwise fastened to the spindle B.

When the attachment is arranged as shown in Figs. 1, 2, 3, 4, and 5 an endless strap, E, passing around the pulley D is supported horizontally by the pulleys F, and in passing over them extends vertically to a point where it passes around and is attached to the pulley G. 55 On a line with the center of this latter pulley we locate friction-rollers H, between which the strap I passes, as shown. This strap forms part of and is connected to the endless strap E, its other end having attached to it a weight, J. 65 This weight is made sufficiently heavy to counterbalance the door A and force it to turn upon its pivot or hinge.

In order to insure that the effective power of the weight shall always be properly directed, 70 we provide a set-screw, K, passing through a bracket attached to the pulley D, and so arranged that it will clamp the strap E to this pulley. Owing to this set-screw it will be possible to set the door so that the effective power 75 of the weight will be exerted upon the door to keep it closed or open, as the case may be. The point to be observed when securing the door to this strap is that the weight J shall be immediately below and on a line with the center of the pulley G. 80

With this description of the construction of our attachment and its connection with the door the operation of the weight will be easily understood. As the door is turned upon its 85 hinge the weight is drawn up by the action of the endless strap E. Immediately the power upon the door is withdrawn the weight J descends, pulling back the endless strap until it regains the position shown in Figs. 2 and 4, carrying 90 with it the door back into its original position. In cases where the door will be arranged to open only in one direction, instead of an endless strap, E, a single strap, I, is carried over a pulley, F, the weight J being attached to it, as 95 in the other case, and it is similarly connected to the pulley D by a set-screw.

When it is desired to use the straps and pulleys we substitute for the pulley D a bevel-spur wheel, D. A bevel-spur wheel, M, supported on 100 a horizontal spindle, N, is set to mesh with the bevel-spur wheel D. The weight J is connect-

ed to the bevel-spur wheel M by the strap, as shown in Figs. 8 and 9, which strap passes between the friction-rollers H, situated as in the other figures. The effect of this arrangement is exactly the same as that described in the other figures. The point where the strap is attached to the spur-wheel M is drawn by the effect of the weight J to a point on a line with its center.

10. In some cases the friction-rollers H may be dispensed with and the weight J attached directly to the bevel-spur wheel M, either cast upon it at the point desired or attached by a rod.

What we claim as our invention is—

15. 1. In a hinged door, A, having a spindle, B, extending from its pivotal point and adjustably supported on the bracket C, a pulley, D, fastened to the spindle B, in combination with an endless strap, E, passing around the pulleys D, F, and G and weighted by the weight J, substantially as and for the purpose specified.

20. 2. In a hinged door having a spindle extending from its pivotal point, a pulley fastened to the spindle, in combination with a strap adjustably fastened to the pulley on the said spindle, and weighted so as to exert a counterbal-

ancing power over the hinged door, substantially as and for the purpose specified.

3. A hinged door, A, provided with a spindle extending from its pivotal point, a horizontal wheel fastened to said spindle, and a vertical wheel connecting with the spindle-wheel, substantially as described, in combination with a weighted strap fastened to said vertical wheel at a point immediately under its center, when 35 in its normal position, as and for the purpose specified.

4. A hinged door, A, provided with a spindle extending from its pivotal point, a horizontal wheel fastened to said spindle, and a vertical wheel connecting with the spindle-wheel, substantially as described, in combination with a weighted strap fastened to said vertical wheel at a point immediately under its center, when 40 in its normal position, and passing between 45 suitable guide-pulleys, as and for the purpose specified.
